POWER TRANSMISSION PUMP

Burton J. Wilson, Detroit, Mich., assignor to
 Vickers Incorporated, Detroit, Mich., a corpora-
 tion of Michigan

Application September 3, 1942, Serial No. 457,163

6 Claims. (Cl. 103—135)

1

This invention relates to power transmissions, particularly to those of the type comprising two or more fluid pressure energy translating devices, one of which may function as a pump and another as a fluid motor.

The invention is more particularly concerned with a pumping unit of the rotary type and with control means for regulating the volumetric discharge thereof.

A form of pump in common use in the hydraulic power transmission field utilizes a rotor having a plurality of substantially radial vanes rotatable therewith and slidable relative thereto. The rotor and vanes cooperate with a stator member which defines one or more pumping chambers through which the vanes pass carrying fluid from the inlet port to the outlet port. Single and multiple units of this character have heretofore been controlled by the use of bypass valves arranged to open an external path connecting the pump outlet with the pump inlet for the purpose of limiting the maximum pressure in the discharge line and also for the purpose of unloading the pump to permit it to circulate fluid idly.

It is an object of the present invention to provide an improved pumping unit which may be unloaded without requiring an external bypass from the discharge port to the suction port of the pump.

A further object is to provide a unit of this character wherein the radial movement of the vanes relative to the rotor may be variably controlled to thereby regulate the pumping action either inhibiting it altogether or causing it to take place in a normal manner.

Further objects and advantages of the present invention will be apparent from the following description, reference being had to the accompanying drawings wherein a preferred form of the present invention is clearly shown.

In the drawings:

Figure 1 is a longitudinal cross section of a pumping unit embodying a preferred form of the present invention.

Figure 2 is a cross section on line 2—2 of Figure 1.

Figure 3 is a cross section on line 3—3 of Figure 1.

Figure 4 is a cross section on line 4—4 of Figure 1.

Figure 5 is a cross section on line 5—5 of Figure 1.

Figure 6 is a cross section on line 6—6 of Figure 1.

2

Figure 7 is a cross section on line 7—7 of Figure 5.

Figure 8 is a cross section on line 8—8 of Figure 5.

Figure 9 is a circuit diagram of the pump unit of Figure 1.

Referring now to Figure 1, there is shown a main body 10 having two cylindrical recesses 12 and 14 in which are mounted rotary pumping units 16 and 18. The latter may be of any suitable type and as shown are similar to the vane pump described in the patent to Harry F. Vickers, No. 1,989,900. An end cap 20 is mounted on the body 10 to retain the pump unit 18 in the recess 14 and carries a bearing 22 in which one end of a shaft 24 is rotatably mounted. An end cap 26 and filler block 28 retain the pump unit 16 in the recess 12, the end cap carrying a bearing 30 in which the other end of the shaft 24 is rotatably mounted. The shaft is splined at 32 and 34 to provide a driving connection for each of the pump units. A suitable mounting flange 36 is secured to the end plate 26 to form a means of attachment of the pump unit to a suitable support. Suitable cap screws or other fastening means, not shown, are provided for holding the end plates at 20, 26 and 36 together.

The pump unit 16 is provided with two diametrically opposite delivery ports 38 and 40 (see Figure 5) and two diametrically opposite suction ports 42 and 44. The body 10 is provided with a cored passage 46 which has arcuate branches 48 and 50 extending partially around the shaft 24 to connect with the delivery ports 38 and 40. The passage 46 forms a delivery conduit for the pump unit 16 and extends to one side (toward the top in Figure 1) of the pumping unit.

The suction ports 42 and 44 of the pump unit 16 communicate with a cored passage 58 having arcuate branches 60 and 62 extending partially around the shaft 24, the branch 62 being disposed radially outward of the branch 50 of the delivery passage 46.

A passage 63 has arcuate branches 64 and 66 which connect with suction ports 68 and 70 of the pump unit 18. The passage 63 has a threaded opening 72 which forms an inlet connection for the pump unit as a whole. A wall 74 which separates the passages 58 and 63 is formed with an opening 76 which forms the seat for a check valve 78. The latter permits free flow from the inlet port 72 to the passage 58 but prevents return flow.

A passage 80 has branches 82 and 84 which connect with outlet ports 86 and 88 of the pump unit 18. The passage 80 has a lateral branch 90

which opens into the passage 46 and an outwardly extending branch 92 which is intersected by a transverse bore 94. The branch 92 connects with a pipe connection 96 forming the discharge outlet of the pump unit as a whole.

The bore 94 has a reduced diameter seat portion 98 adjacent the lefthand wall of passage 92 in Figure 4 and extends beyond the seat portion 98 to connect with a pipe connection 100 forming an overflow port for the unit as a whole. Slidably mounted in the bore 94 is a relief valve 102 having a conical valve portion 104 normally closing the seat 98. The end of the bore 94 is closed by a cap 106 having therein an adjustable pilot relief valve 108 adapted to control the operation of valve 102. The construction and operation of the valve 102 and its control by the pilot relief valve 108 are described in detail in the patent to Harry F. Vickers, No. 2,043,453, to which reference is made for further detail. Briefly, the valve 102 acts to maintain the passage 92 cut off from communication with the relief passage 100 until a predetermined maximum pressure is reached in the passage 92, at which point the valve 102 opens to whatever degree may be required to prevent the pressure from rising beyond that point.

As seen particularly in Figure 3, there is formed in the body a small bore 110 provided with three spaced enlargements 112, 114 and 116. The upper end of the bore 110 communicates with the extension 92 of passage 80 through a duct 118. A duct 120 connects extension 92 with the enlargement 112. A duct 122 connects the port 100 with the enlargement 116. Slidably in the bore 110 is a valve spool 124 which is urged upwardly in Figure 3 by a spring 126. The latter is adjustable by means of a screw 128. It will be seen that the spool 124 is shiftable in response to pressure variations in extension 92 and, when shifted downwardly by a rise in pressure, connects the central enlargement 114 with the overflow port 100, while, when the valve is shifted upwardly by a fall in pressure, the central enlargement 114 is connected with the pump discharge pressure at extension 92.

As seen in Figure 1, the pump unit 16 is provided with a pair of circumferential grooves 130 which communicate with the inner end of the slots in which the vanes of unit 16 slide. These circumferential grooves 130 connect by a duct 132 with the central enlargement 114 in valve bore 110. Similar circumferential grooves are preferably provided in connection with the pump unit 18 but are permanently connected with the pump pressure supply in a manner well known in the art.

In operation, referring particularly to the circuit diagram of Figure 9, it will be seen that, with both pump units 16 and 18 being driven by the rotation of drive shaft 24, fluid will be taken in through the inlet port 72, a minor fraction going through passage 63 to the inlet ports 68 and 70 of pump unit 18 and a major portion passing through check valve 78 and passage 58 to the inlet ports 42 and 44 of pump 16. The units transfer the fluid to their respective delivery ports, such fluid passing from the passages 46 and 80 past the relief valve 102 and out through the discharge connection 96.

When the fluid requirements of the device which is being driven by the fluid output of the pump are such as to impose only light or medium resistance to the flow of fluid, the pressure in discharge conduit 80 will be low, and the spring 126 will hold the valve 124 in its righthand posi-

tion in Figure 9. Accordingly, the pump discharge pressure will be connected through duct 120, enlargements 112 and 114, and duct 132 to the circumferential grooves 130. Thus, fluid pressure is maintained beneath the vanes of the unit 16 to keep them projected into tight contact with the circumferential walls of the pump working chamber. This operation of unit 16 is conventional and identical to that of the unit 18 under these conditions.

As soon as the load device imposes additional resistance so that the pressure in discharge conduit 80 builds up sufficiently to push valve spool 124 to the left in Figure 9, the circumferential grooves 130 become connected to the exhaust side of the pump through duct 132, enlargements 114 and 116, duct 122 and port 100. The pressure in passage 46, however, is applied adjacent the discharge ports 38 and 40 to the radially outer end of the vanes and, accordingly, causes them to retract inwardly, thus opening a free path from the discharge ports 38 and 40 to the suction ports 42 and 44. Accordingly, the vanes around the entire circumference of the rotor are subject to full pump pressure from the unit 18 applied to their outer end, and they are thus prevented from being projected by centrifugal force into contact with the walls of the pump chamber.

The discharge pressure, although it backs up into the suction ports 42 and 44 of pump unit 16, is prevented from bypassing to tank by the check valve 78. In this way, a higher degree of pressure may be built up in the discharge port of the pump by the small-volume pumping unit 18, and the large-volume unit 16 is rendered ineffective as a pump. The valve 102 acts in the manner of a conventional relief valve to limit the maximum pressure which can be applied to the pump as a whole.

It will be seen that a two-volume pumping unit of this character is particularly adapted to those types of circuits wherein a large volume of fluid is required against a fairly low pressure and at other times a smaller volume is required at a much higher pressure. Circuits of this nature are commonly found in machine tool drives wherein the large volume is required for rapidly advancing a machine part to its working position and wherein the small volume is required for slowly feeding the part on its actual working stroke.

It will be noted that, during the operation of the small-volume pump alone, the large-volume pump is not bypassed but is rendered entirely non-operative by the action of fluid pressure on the radial vanes. In this way, the wear on the ends of the vanes as well as the wear on the peripheral face of the pumping chamber is materially reduced as compared with previous methods of unloading a pump of this nature.

While the form of embodiment of the invention as herein disclosed constitutes a preferred form, it is to be understood that other forms might be adopted, all coming within the scope of the claims which follow.

What is claimed is as follows:

1. A pump unloading system for rotary vane type pumps of the type having a vane-projecting pressure chamber effective when the pump is in operation to project the vanes into operative position, said pump having a suction inlet and a discharge outlet, a second pump in communication with said outlet for maintaining pressure therein independently of the effective opera-

tion of the first pump, a valve for selectively causing fluid pressure to build up or to fall off in said chamber, and a check valve on the suction side of said pump to prevent exhausting of fluid from the discharge to the suction side when pressure falls off in said chamber and the vanes are consequently retracted from operative position.

2. A rotary vane type pump having an inlet and an outlet and alternately retractable and extendable vanes for sealing the passage of fluid between the pump inlet and the pump outlet, a check valve at the pump inlet, means for selectively controlling the application or removal of pressure to said vanes to at times maintain the vanes continuously retracted whereby such sealing is prevented and the pump is rendered inoperative while continuing to rotate, and means for maintaining pressure in said outlet during non-operation of said pump.

3. A rotary vane type pump having an inlet and an outlet and alternately retractable and extendable vanes for sealing the passage of fluid between the pump inlet and the pump outlet, a check valve at the pump inlet, means for selectively controlling the application or removal of pressure to said vanes to at times maintain the vanes continuously retracted whereby such sealing is prevented and the pump is rendered inoperative while continuing to rotate, and a second pump having its outlet connected with that of the first pump to maintain pressure therein during nonoperation of the first pump.

4. A multiple delivery rate pumping unit comprising a plurality of pumps driven from a common drive shaft, one of said pumps being of the rotary type and having working elements adapted to be selectively rendered inoperative during rotation of the pump or placed into operation, and fluid pressure applying means for selectively ef-

fecting such inoperativeness or operation, another of said pumps remaining in operation and being connected to said pressure applying means during inoperativeness of the first pump whereby pressure is maintained available for said pressure applying means.

5. A multiple delivery rate pumping unit comprising a plurality of pumps driven from a common drive shaft, one of said pumps being of the rotary type and having working elements adapted to be selectively rendered inoperative during rotation of the pump or placed into operation, fluid pressure applying means for selectively effecting such inoperativeness or operation, another of said pumps remaining in operation and being connected to said pressure applying means during inoperativeness of the first pump whereby pressure is maintained available for said pressure applying means, and a check valve connected with the first-mentioned pump for preventing backflow therethrough while the pump is inoperative.

6. A multiple delivery rate pumping unit comprising a plurality of pumps driven from a common drive shaft, one of said pumps being of the rotary type and having working elements adapted to be selectively rendered inoperative during rotation of the pump or placed into operation, fluid pressure applying means for selectively effecting such inoperativeness or operation, another of said pumps remaining in operation and being connected to said pressure applying means during inoperativeness of the first pump whereby pressure is maintained available for said pressure applying means, and a check valve located in the inlet of the first-mentioned pump for preventing backflow therethrough while the pump is inoperative.

BURTON J. WILSON.
